UNITED STATES PATENT OFFICE.

WALTER LAMBERT, OF MONTREAL, QUEBEC, CANADA.

CARGO VESSEL.

1,400,298.

Specification of Letters Patent. Patented Dec. 13, 1921.

Application filed January 6, 1921. Serial No. 435,507.

To all whom it may concern:

Be it known that I, WALTER LAMBERT, a subject of the King of Great Britain, and residing at 14 Place Royale, in the city and 5 district of Montreal, in the Province of Quebec, in the Dominion of Canada, have invented a new and useful Cargo Vessel, of which the following is the specification.

The invention relates to cargo vessels as 10 described in the present specification and illustrated in the accompanying drawings that form part of the same.

The invention consists essentially in the 15 novel construction whereby the discharge of bulk cargo, lighter than water, is facilitated by the particular cross-sectional shape of the side walls and the open boat form of holds.

The objects of the invention are to facilitate the discharging of cargoes like pulp- 20 wood so that much time will be saved and the vessel thereby permitted to make so many more trips during the season; to econo- 25 mize in the matter of unloading expenses by using natural facilities, and consequently to float the cargo out of the hold, which will materially decrease the expenses of labor in the handling of the wood; and generally to provide a staunch and reliable cargo vessel 30 which may be readily discharged of its cargo at its destination.

In the drawings, Figure 1 is a side elevation of the vessel.

Fig. 2 is a plan view showing the cargo space, the bulkheads, and the air-tight com- 35 partments separating the hold into its divisional arrangement.

Fig. 3 is a perspective detail showing, in skeleton form, the divisional arrangement as 40 illustrated in the plan view in Fig. 2.

Fig. 4 is a fragmentary sectional detail of the side wall and coaming in lip form.

Fig. 5 is a fragmentary sectional view of the side wall at an intermediate point between a bulkhead and the middle framing of 45 a cargo compartment.

Fig. 6 is a cross-sectional view illustrating the operation of discharging the cargo.

Like numerals of reference indicate corresponding parts in each figure.

Referring to the drawings, the hull 1 is 50 built up from the bottom 2, around the framing formed of the vertical beams 3, lower transverse beams 4, and bulkheads 5. The vertical beams 3 extend upwardly in a 55 perpendicular section 6 from the bilge plates 7, and in the converging sections 8 to the

flaring bulwarks 9, having the downwardly turned lips 10.

The rubbing strips 11 extend along the sides just below the knees 12 of the vertical 60 beams 3.

The stiffening brackets 13 are arranged between beams and bulkheads, and the guiding plates 14 facilitate the passage of the 65 wood over said brackets.

The vertical beams 3 are joined just below the bulwarks 9 by the upper transverse girders 15, and these transverse girders are midway between the bulkheads 5 of each cargo 70 space.

The end walls of each cargo space are the bulkheads 5, and these bulkheads form the open compartments 17, which extend upwardly to the bulwarks 9, and are throughout completely clear of covering so that the 75 hull is an open boat between the machinery at the stern and the crew's quarters at the bow.

The walking bridge 19, is built in centrally over the bulkheads 5, and is substantially 80 flush with the said bulkheads, and is supported intermediately by the transverse girders 15 on the brackets 20.

The monitor track 21 is secured to the walking bridge 19 and the hose line guides 85 22 are arranged between the rails of said track and on this track a monitor 23 travels and carries the swinging nozzle 24 connected to the hose 25 in the said hose guides 22, and connected to any water under 90 pressure.

The flooding pipe line 31 is connected to a pump 32, operated by the machinery of the vessel or in any suitable way, and runs along the bottom of the vessel throughout the 95 whole length of the open cargo space and is fed by said pump 32, which draws the water to the pipe 31 and forces it out of one or more ports closed by the valves 33 operated by the wheels 34 from the walking 100 bridge 19.

The main discharge pipe 35 runs along the bottom of the cargo space through the several open holds and is connected to a pump 36 which draws the water from the holds 105 through the ports closed by the valves 37 the latter being operated by the wheels 38 from the walking bridge 19.

The doors 39 swing on hinges 40 and open a discharge for wood through said bulwarks 110 though most of it will float over yet considerable will be carried through the openings

made by throwing these doors down, as there is a rush of water from the discharging compartment, and this rush of water will serve to carry the wood with it.

5 In the operation of this vessel, it will be seen that the hull, with the exception of a short space at the stern for the machinery and officers, and a short space at the bow for crew and landing facilities, is taken up by the 10 cargo space; in fact, it is practically a large open boat between ends, with no hatches though necessarily the hull must be strengthened intermediately by a transverse framing; and also bulkheads for dividing the 15 cargo space up into holds, so that the operation of discharging may be done one at a time to guard the safety of the vessel.

The wood is loaded into these holds in the well known manner familiar to the transportation of such cargoes, and is piled as 20 high up as possible without running the risk of losing it. A hold of the vessel is flooded when it arrives at its destination, preferably one at a time, so as to avoid any danger of capsizing, and to avoid excessive trim while the discharge is being made.

The water in the flooded hold will carry the wood to the top of the bulwarks and thereover, though most of the wood will pass 30 through the openings cleared by swinging the discharge doors downwardly. As soon as the wood is discharged from any one hold

that hold is emptied, that is to say, it is pumped out and cleared of water, and the same operation is carried out with the next 35 hold, and so on until they are all cleared; of course it may be possible to clear two or three at once; in fact, as many as the conditions in discharging will permit, the main object being to clear the cargo space of the 40 wood by natural means.

What I claim is:

1. In a cargo vessel, a hull having side walls converging from a point intermediate of their height and flaring at their upper 45 ends and terminating in a downwardly turned lip, transverse bulk heads and frames bracing said sides and leaving an open hold from the said sides inwardly and means for driving the floatable cargo over the flaring sides movable longitudinally of the vessel.

2. A cargo vessel having a plurality of partitions and transverse framing dividing the cargo compartment of a hull in open boat 55 formation, a walking bridge over said compartment from end to end, a monitor traveling on said bridge and having nozzle therefrom and water connections to said monitor supported by said bridge.

Signed at Montreal, Quebec, Canada, this 30th day of December, 1920.

WALTER LAMBERT.
